1

Our invention pertains to the handling and cooling of a chase and its contents, a chase being an articulated rectangular steel frame within which a page of type and/or plates and cuts are locked either for printing directly or for making a mat or matrix, and the invention being expressed both as a method and as a mechanism.

Over the course of the past twenty-five years, the art of stereotype printing in color rapidly has advanced both as concerns the speed and the quality of the printing and as concerns the excellence of detail in the execution thereof. These forward strides today are evident in the multi-colored comic and magazine sections of large newspapers, in the excellent detail obtained in multi-colored advertising broadsides and other literature, and in the colored pictures and advertising of magazines. In a broad sense, the instant invention is directed toward an improvement in and in a further step forward in the art of stereotype printing in color.

To provide a setting for and to appreciate the advantages and improvements accomplished by the instant invention, a typical stereotype make up and processing operation will be examined. In a large metropolitan newspaper, by way of example, a multi-color magazine or "farm and home" section often accompanies the Sunday edition of the paper. Let it be assumed that a particular double page of one such section is to be printed in three colors on a high speed rotary press. Firstly, the lead type plates and/or partial cuts are assembled in a steel chase which rests upon a smooth topped work table, the entire assembly often weighing 160 to 200 pounds and being almost impossible to lift by the edges without losing a small space slug or line of type. After make up, the chase very carefully is moved by cart to a so-called "direct pressure machine" for the practice, well known to those skilled in the stereotype printing art, of the "hot molding process." In brief, this process is practiced with a direct pressure machine having a large hydraulic pressure platen capable of exerting a vertical compressive force of from 600 to 900 tons. The pressure platen, in turn, is equipped with an electric heater, of twenty kilowatt or larger size, capable of heating the platen to a controlled temperature of from 250 to 300° F.

Continuing with the preparation of the rotary press stereotypes, the made up chase is positioned in the pressure machine and a dry mat having a cellulose fiber base is laid over the top of the chase. The platen then descends upon the mat to heat and press the latter against the face of

2

the type and cuts with a compressive force of about 600 or 700 tons. After seven to fifteen minutes under this pressure and heat, the mat has cured and baked sufficiently to have impressed thereon a reverse copy of the contents of the chase. The finished mat then is removed from the pressure machine and hot lead is poured thereover to cast a cylindrical stereotype for the rotary press. In the meantime, the chase, with care and finesse, is removed from the pressure machine and, conventionally, is left to cool to room temperature. After cooling, certain of the partial cuts and type may be changed to make up a layout for the second of the three colors. The hot molding process and the casting from the mat then are repeated to form a second stereotype. When three such stereotypes have been cast, they are positioned serially on three adjacent cylinders of a high speed rotary press and each is inked with a different color. Thereafter, when a sheet of newsprint is fed past the three cylindrical stereotypes, it is printed in three successive colors, one on top of or complementary to the other, to form a complete multi-color sheet, two tabloid size pages conventionally being printed at the same time.

That particular portion of the above described process with which the instant invention most directly is concerned involves the treatment of the chase between the time one mat is formed and the time the next lay out is made up. Thus, each time the hot molding process is practiced, whereby a dry mat is pressed, baked, and cured in the direct pressure machine, the temperature of the chase and its contents are elevated to the temperature of the platen (approximately 300° F.). Needless to relate, this indirect heating of the steel chase and its lead contents is undesirable and is provocative of several problems. However, it cannot be avoided since a true dry mat impression requires the application of both heat and pressure by the platen. One undesirable feature of the increase in temperature is that the lead type, plates, and cuts expand much more than the steel chase, lead having a coefficient of expansion approximately three times as great as that for steel. Further, this differential expansion problem is amplified by the fact that the alignment of the cuts and/or plates within the chase must be maintained true and exact in successive make ups if the colors are to match with a sharp demarcation and detail on the printed page. Still further, the melting point of the lead parts within the chase is somewhat less than 600° F. and, under the six to nine

hundred ton pressure of the platen, these parts will begin to flow and to produce a blurred image at even lower temperatures. Each of the above factors serves to illustrate the importance of keeping the chase as cool as possible during the molding process and of cooling the chase and the lead contents thereof after each practice of the process. The instant invention is directed toward an improved method and mechanism for cooling a chase in accord with the above listed requirements.

Accordingly, one object of our invention is to provide a refrigeration device for cooling a chase, said device to be capable of handling the chase expeditiously and carefully so that none of the type will be lost therefrom due to contraction during the cooling process and so the various lead elements (the type and plates) will not be displaced or disturbed during handling both before and after cooling.

Another object of our invention is to provide a novel method of treatment for cooling a chase from a temperature of approximately 300° F. to a temperature of 70° F. in the shortest possible time and without disturbing the delicate and critical alignment of the elements within the chase, to the ultimate end that the type and cuts thereafter may be manipulated with the bare hands and may be interchanged preparatory to pressing another mat therefrom.

In satisfaction of the above objectives, our invention provides an insulated hollow cabinet having a cooling compartment therein with refrigeration means for circulating refrigerated air about the compartment. Additionally, a heat conductive slab of metal extends laterally across the cooling compartment and is provided with a smooth plane top surface. The rear margin of this slab is mounted upon pivot means lying within a fixed horizontal datum plane, the definition of such a plane being important to the careful handling of a chase. Actuation means, operable from without the cabinet cooperate with the datum plane pivot means to articulate the slab as an entity between a lower position in which the plane top surface thereof is below the datum plane and a raised position in which the top surface is above the datum plane, the total movement between these positions being substantially less than one-quarter inch. Accordingly, when a heated chase of type is brought to the cabinet for cooling, it is transported in the fixed horizontal datum plane above defined. Thereafter, the slab is pivoted to the lower position so as to lie approximately one-eighth of an inch below the datum plane and the chase, together with its lead contents, is slid from the datum plane onto the slab. The refrigeration mechanism then is actuated to cool the chase uniformly and quickly as hereinafter will be described. The slab then is pivoted to the raised position so the front margin of the top surface thereof will lie approximately one-eighth inch above the datum plane. From this raised position, the chase once more can be slid out of the cabinet and into the fixed horizontal datum plane without disturbing the alignment of the contracted lead type and plates. Further in contrast with the conventional practice by which the chase was left at room temperature for about three hours during the cooling process, our novel refrigeration device will cool the entire chase at a uniform rate and progressively from both surfaces thereof in approximately four minutes. In labor cost alone, this speed-up effects a con-

siderable saving since the assembly of a complete three color stereotype can progress no faster than the cooling of the chase.

In accord with the method definition of our invention, a uniform cooling of the chase is effected progressively toward the center of the type and plates from both faces thereof. This method includes the steps of providing a heat conductive slab having a substantially horizontal smooth plane surface, positioning the heated chase upon a horizontal datum plane immediately adjacent but just above the plane surface of the slab, sliding the chase from the datum plane onto the said plane surface, blowing refrigerated air over the exposed surfaces of both the chase and the slab until the temperature of the former is reduced sufficiently to allow manipulation thereof with the bare hands, raising a portion of this slab vertically until the plane surface thereof is substantially coextensive with but slightly above the horizontal datum plane, and sliding the cooled chase off of the plane surface and onto the datum plane for further processing and use.

In summary, our refrigeration mechanism and the practice of our inventive method provide a faster, more uniform, and less expensive cooling of the chase. Further, the precise and deliberate handling of the chase during and after cooling assure a minimal disturbance of the critical positioning of the type and plates within the chase so that excellent detail on the printed page is assured.

The above and other inventive objects, capabilities and advantages inherent in and encompassed by our invention will become apparent from the ensuing description, taken in conjunction with the accompanying drawings, wherein:

Fig. 1 is a perspective view of the refrigeration device of our invention showing a chase in the process of being admitted thereto;

Fig. 2 is a sectional front to rear view looking through the cooling compartment of our refrigeration device substantially as indicated by the arrows 2-2 in Fig. 3 and showing a chase in the process of being cooled, the direction of movement of the circulating refrigerated air about the heat conductive slab and the top of the chase being indicated by small arrows;

Fig. 3 is a sectional side view of our invention, with the relative positions of the heat conductive slab and the chase exaggerated somewhat, better to illustrate the manner in which the chase is moved into the cooling compartment without disturbing the type and plates; and

Fig. 4 is a partial detail view similar to Fig. 3 in the amount of exaggeration but illustrating the raised position of the heat conductive slab whereby the chase may be removed from the cooling chamber without disturbing its contents.

Our refrigeration device particularly is designed for the treatment of a steel chase, such as is shown at 5. To this end, the articulated parts of the refrigerator must be capable of precise and exact adjustment so as not to disturb the type and the plates carried within the chase. Thus, when completely made up preparatory to having a mat for multi-color stereotype printing pressed therefrom, a chase is the size of a full newspaper page and it weighs 160 to 200 pounds or more. Further, as well known in the printing art, a chase should not be lifted by the edges or a line of type or a small space slug will fall out. Accordingly, it is handled with great

care and is moved about in the stereotype department on large carts or wagons 6 having smooth flat tops 7 thereon. In sequence, the chase will be made up on a smooth table top, will be slid off of the table and onto the flat top 7 of the cart 6, will be slid from this top 7 to the flat work area of a direct pressure machine, will be removed from the pressure machine to a similar cart 6 and, thereafter, will be admitted to the refrigeration device of our invention, each such movement being effected with care by butting two substantially parallel flat surfaces together and sliding the chase from one surface of the other.

In detail, our refrigerator has a cabinet 8 which stands upon four legs 9. Each of these legs, in turn, carries a leveling screw 10 which defines one portion of a variable level means. Thus, the cabinet is supported adjustably in order that the various elements of the refrigerator may be leveled with respect to a horizontal datum plane as hereinafter will be described.

Progressing now to the structural details of the cabinet 8, a plurality of insulated walls, including a front wall 11, a back wall 12, and side walls 13, are arranged to bound a cooling chamber 14. Additionally, a laterally elongated rectangular opening 15 pierces the front wall 11 to provide access to the cooling chamber 14 from without the cabinet. In cooperation therewith, an insulated door 16 is mounted pivotally upon the front wall selectively to close or to expose the opening 15. During the cooling process, of course, the door is closed to inhibit the entrance of heat into the cooling chamber.

Within the cooling chamber 14, we mount a large heat conductive slab of metal, such as aluminum, 17 and, in accord with the previously mentioned leveling screws 10, this slab is disposed in a substantially horizontal plane. The top of the slab, as shown in the drawings, is machined to a smooth plane surface and the bottom thereof, as indicated at 18 in Fig. 2, is corrugated or finned to enhance the thermal conductivity of the slab and to intercept air blown thereacross. Further, as a comparison of Figs. 2 and 3 will reveal, the slab 17 extends completely across the cooling compartment from front to back but it terminates short of the side walls 13. Accordingly, a circulation duct or open space 19 is defined intermediate the side margins of the slab 17 and the side walls 13 for a purpose hereinafter to be described.

At this point, an important feature of my invention will become evident. Thus, the rear margin of the slab 17 is mounted upon a hinge 20 and the front portion thereof is carried upon two eccentric cams 21. The cams 21, in turn, are keyed to a transverse shaft 22 which is journaled in the opposite side walls 13 of the cabinet and which protrudes beyond one side of the cabinet to terminate in a crank arm 23. When the crank arm 23 is rotated, the eccentric cams 21 serve to pivot the slab 17 about the hinge 20.

In cooperation with these last described elements, I have shown a "datum plane" in Figs. 3 and 4. This datum plane is horizontal and the smooth flat top 7 of the cart 6 lies exactly within the datum plane, the various elements of the refrigerator cabinet being correlated to the position of the datum plane by adjusting the leveling screws 10. For example, the hinge 20 for the slab 17 preferably is correlated with respect to and is parallel to the datum plane. The eccentric cams 21, in turn, are correlated to the position

of the slab so the smooth top surface of the latter is pivotable back and forth through intercepting relationship with the datum plane. In this manner, the cams define an actuation means operable to pivot the slab 17 between a lower position in which the plane top surface thereof is below the datum plane (see Fig. 3) and a raised position in which the top surface is above the datum plane (see Fig. 4). Generically, the angle traced by the pivotal movement of the slab between these positions is bisected by the fixed datum plane and the overall vertical movement of the front edge of the slab is approximately $\frac{1}{16}$ of an inch or, in any event, is less than one-half inch.

Turning now to Figs. 2 and 3, the cooling chamber 14 is provided with refrigeration means for circulating refrigerated air about the slab 17 and through the compartment. This refrigeration means takes the form of a conventional compressor motor mechanism 24 having the usual refrigerant lines 25 joined thereto. At the top of the cooling chamber 14, on the other hand, a rectangular tunnel may be defined and bounded as by a plurality of thin walls 26. Within this tunnel, the refrigerant lines 25 are formed into evaporator cooling coils 27. Further, a motor driven fan 28 is aligned with the coils 27 and is directed laterally across the cooling compartment 14. When operated, this fan blows and circulates air across the coils 27 and around the interior of the cabinet. A portion of this refrigerated air circulates down one of the ducts 19 and up the other duct 19 as shown by the arrows in Fig. 2. In result, this portion of the refrigerated air coacts with the corrugations 18 on the bottom of the slab to cool the slab, and, thereby, to cool the chase 5 from the bottom up. A second portion of the refrigerated air, as indicated by further arrows in Fig. 2, is blown across the top of the chase 5 to cool the latter from the upper surface down. Thus, the chase 5 is cooled at a substantially uniform rate inwardly from both surfaces thereof, the circulation of the refrigerated air, the conductivity of the metal slab 17, and the fins or corrugations carried by the slab all cooperating to produce this desired uniformity.

In order to retrieve the chase 5 from the interior of the cabinet, we provide an elongated hook 29 having a handle 30 on one end thereof and a perpendicular plate 31 on the other end thereof. This hook is guided in an appropriate bracket carried by the front wall 11 of the cabinet and is movable in a direction substantially parallel to the top of the slab 17 to retrieve the chase 5. If desired, the insulated door 16 may have a cutaway portion 32 therein within which the handle 30 rests when the door is closed. The facts that the chase 5 is massive and that the opening 15 provides only limited access to the cooling chamber of the cabinet require the use of a hook of this type.

The operation of my refrigeration device will be described with respect to that portion of a color stereotype process which takes place between the hot mold formation of a dry mat and the changing of the type and/or the plates within the chase. Thus, when the chase 5 leaves the direct pressure machine (previously described), it has a uniform elevated temperature of between 250 and 300° F. Accordingly, it is moved onto the smooth top 7 of the cart 6 with an appropriate push rod or it is handled with gloves. In either event, the chase must be handled with

care so the alignment of the type and plates will not be disturbed. After loading, the cart is wheeled to the cabinet 8 where it is positioned in abutment with the end of the slab 17, the leveling screws 10 previously having been adjusted to match with the cart. Thereafter, the slab 17 is lowered to the position of Fig. 3 so as to lie slightly below the "datum plane" in which the top of the cart lies. This disposition of the slab, of course, is effected by manipulating the crank arm 23 to turn the eccentric cams 21 and, thereby, to pivot the slab about the hinge 29 which lies parallel to and substantially within the datum plane.

When correctly positioned, the chase 5 is pushed and is slid off of the flat top 1 and onto the smooth surface of the slab 17 as indicated by the movement arrow in Fig. 3. Once the heated chase is in place upon the slab, the door 16 is closed and the chase is cooled by circulating refrigerated air thereover as shown in Fig. 2. This refrigeration process, in practice, will lower the temperature of the chase from about 300° F. to about room temperature (or 70° F.) in four minutes or less when the refrigeration mechanism is operating efficiently. Further, the chase is cooled uniformly both from the bottom and from the top due to the novel divided circulation of the cooled air and to the fin or corrugation elements on the bottom of the heat conductive slab 17. If such uniformity were not maintained, the lead might become misaligned due to the different rates of contraction of the steel and lead and because of a differential contraction within the lead parts per se.

After the steel chase and the lead contents thereof have been cooled sufficiently, the door 16 is swung open and latched, as indicated at 33, and the crank arm 23 is manipulated. This manipulation of the crank arm raises the slab 17 pivotally by rotation of the eccentric cams 21. In the raised position (see Fig. 4), the top surface of the slab 17 lies slightly above the datum plane so the chase may be transferred from the slab to the cart without disturbing the type and the plates. This transfer is effected by pulling on the handle 30 so the plate 31 of the hook contacts the back of the chase. After transfer, of course, the chase once more is ready for processing and for use in forming a second or a third mat from which a different stereotype color plate will be cast. In practice, the precise disposition of the slab relative to the datum plane has proven very effective and, even with a minimum of care and patience, the chase can be transferred to and from the refrigerator without disturbing the type and plates.

Defining our invention as a method, we first set forth a combination which includes a chase having a page of type and plates fastened therein, said chase and the contents thereof having a substantially uniform elevated temperature exceeding 200° F. The method then becomes one for treating and for cooling the chase and contents without disturbing the critical alignment of the type and plates and to the end that the various elements thereafter may be manipulated with the bare hands. The first step of the method is to provide a pivotally mounted heat conductive slab 17 having a substantially horizontal smooth plane top surface. This horizontal arrangement of the slab surface is effected with the leveling screws 10. Additionally, the heated chase is positioned and rested upon a horizontal datum plane immediately adjacent but just

above the plane surface of the slab as shown in Fig. 3. Thereafter, the method progresses as the chase is slid from the datum plane onto the plane surface and refrigerated air is blown over the exposed surfaces of both the chase and the slab until the temperature of the former is reduced sufficiently to allow manipulation thereof with the bare hands. Prior to removing the chase, the slab is pivoted upwardly until the plane top thereof is raised slightly above the datum plane. The total vertical movement of the front margin of the slab between these two positions is less than one-half inch and the angle traced by the pivotal movement is bisected by the datum plane. Finally, the method is concluded when the cooled chase is slid from the plane surface onto the datum plane for further processing and use.

In summary, I have provided both a mechanism and a method for cooling a chase without disturbing the critical and delicate arrangement of the contents thereof. Further, the chase can be cooled in a minimal time so that the mat forming equipment will not be tied up and so the other steps of the process for forming stereotype color plates can proceed substantially immediately and without delay. In actual practice, this invention has resulted in substantial savings in processing color work on a large metropolitan newspaper and, additionally, the detail of this color work has been improved materially.

We claim:

1. A refrigeration device for cooling a chase, comprising an insulated hollow cabinet having a cooling compartment therein, refrigeration means mounted within said compartment for circulating refrigerated air thereabout, said cabinet having an opening through one wall thereof providing access to the cooling compartment, a substantially horizontal heat conductive slab extending laterally across said cooling compartment and terminating within the bounds of said opening, said slab having a smooth plane top surface and an irregular bottom surface, pivot means lying parallel and closely adjacent to a fixed horizontal datum plane and joined to that margin of the top surface of the slab which is remote from said opening to mount the slab for pivotal movement about the said margin, and actuation means for pivoting said slab between a lower position in which said plane top surface is below said datum plane and a raised position in which the top surface is above the datum plane, the angle traced by the pivotal movement of said slab between said positions being bisected by said fixed datum plane.

2. A refrigeration device for cooling a chase which initially is at a temperature exceeding room temperature, comprising an insulated hollow cabinet having a cooling compartment therein, refrigeration means including a coil and a fan mounted within said compartment to circulate refrigerated air thereabout, a heat conductive slab of metal extending laterally across said cooling compartment, said slab having a smooth plane top surface, pivot means lying substantially within a fixed horizontal datum plane and joined to one margin of the slab to mount the slab for pivotal movement about the said margin, actuation means operable to pivot said slab between a lower position in which said plane top surface is below said datum plane and a raised position in which the top surface is above the datum plane, the angle traced by the pivotal movement of said slab between said positions being bisected by said

fixed datum plane, and variable level means supporting said cabinet adjustably to position the said top surface margin of the slab within said horizontal datum plane.

3. A refrigeration device, comprising a cabinet having insulated front, back and side walls bounding a cooling compartment, a substantially horizontal heat conductive slab mounted pivotally within said cooling compartment, said slab extending completely across said cooling compartment from front to back terminating short of the side walls thereof to define two side circulation ducts intermediate the side margins of the slab and the side walls, actuation means bearing upon said slab selectively for pivoting the slab about said pivotal mounting, refrigeration means mounted within said cooling compartment to cool the air within the compartment, and fan means aligned with said coil and directed laterally across said compartment to blow cooled air through said side circulation ducts and across said slab.

4. A refrigerator for cooling a chase, comprising a cabinet having insulated front, back and side walls bounding a cooling compartment, a substantially horizontal heat conductive slab of metal mounted pivotally upon said back wall within said cooling compartment, said slab having a smooth plane top surface, the pivotal mounting for said slab lying closely adjacent and parallel to a horizontal datum plane and the smooth top surface of the slab being movable with the slab back and forth through intersecting relationship with said datum plane, actuation means bearing upon said slab selectively for pivoting the front of the slab about said back wall pivotal mounting, and refrigeration means within said cooling compartment for cooling the same.

5. A refrigerator for cooling a chase and the contents thereof after they have become heated during use, comprising a cabinet having insulated front, back and side walls bounding a cooling compartment, said front wall having a laterally elongated opening therethrough to provide access to the cooling compartment from without the cabinet, an insulated door means mounted pivotally upon said front wall selectively to close or to expose said elongated opening, a substantially horizontal heat conductive slab mounted pivotally within said cooling compartment, said slab extending completely across said cooling compartment from front to back, actuation means bearing upon said slab selectively for pivoting the front of the slab about said pivotal mounting, said actuation means including a lift element joined operatively to a crank which is mounted without the cabinet, and refrigeration means within said cooling compartment for circulating refrigerated air about said slab and through the compartment.

6. A refrigerator for cooling a chase, comprising a cabinet having insulated front, back and side walls bounding a cooling compartment, a substantially horizontal heat conductive slab mounted pivotally within said cooling compartment, said slab extending completely across said cooling compartment from front to back but terminating short of the side walls thereof to define two side circulation ducts intermediate the side margins of the slab and the side walls, said slab having a smooth plane top surface, the pivotal mounting for said slab lying parallel to a horizontal datum plane and the smooth top surface of the slab being movable with the slab back and

forth through intersecting relationship with said datum plane, actuation means bearing upon said slab selectively for pivoting the front of the slab about said pivotal mounting, an elongated hook means extending through said opening and mounted for retraction across the cooling compartment to retrieve objects resting on the said top surface of the slab, a refrigerated coil means mounted within said cooling compartment above said slab to cool the air within the compartment, and fan means aligned with said coil and directed laterally across said compartment to blow cooled air through said side circulation ducts and across said slab.

7. A refrigerator for cooling a chase and the contents thereof after they have become heated during use, comprising a polygonal cabinet having a plurality of insulated walls including front, back and side walls bounding a cooling compartment, said front wall having a laterally elongated rectangular opening therethrough to provide access to the cooling compartment from without the cabinet, an insulated door means mounted pivotally upon said front wall selectively to close or to expose said elongated opening, a substantially horizontal heat conductive slab of metal mounted pivotally within said cooling compartment, level means supporting said cabinet to adjust the horizontal disposition of said slab within limits, said slab terminating substantially flush with said elongated opening and having a smooth plane top surface and a corrugated bottom surface, actuation means bearing upon said slab selectively for pivoting the front of the slab about said pivotal mounting, said actuation means including a lift element joined operatively to a crank which terminates without the cabinet, an elongated hook means extending through said opening and mounted for retraction across the cooling compartment in a direction substantially parallel the top surface of said slab to retrieve objects resting on the said top surface, and refrigeration means within said cooling compartment for circulating refrigerated air about said slab and through the compartment.

8. A method for treating a chase and its contents after they have become heated to an elevated temperature during use, said method including the steps of providing a heat conductive slab having a substantially horizontal smooth plane surface, positioning the heated chase upon a horizontal datum plane immediately adjacent but just above the plane surface of said slab, sliding said chase from said datum plane onto said plane surface, blowing refrigerated air over the exposed surfaces of both the chase and the slab until the temperature of the former is reduced sufficiently to allow manipulation thereof with the bare hands, raising a portion of said slab vertically until the plane surface thereof is substantially coextensive with but slightly above said horizontal datum plane, and sliding the cooled chase off of said plane surface and onto said datum plane for further processing and use.

9. In combination with a chase having a page of type and plates fastened therein, said chase and the contents thereof having a substantially uniform elevated temperature exceeding 200° F., a method for treating and cooling the same without disturbing the critical alignment of the contents within the chase and to the end that the various elements thereafter may be manipulated with the bare hands, said method including the steps of providing a pivotally mounted heat conductive slab having a substantially horizontal

11

smooth plane surface, positioning and resting the heated chase upon a horizontal datum plane immediately adjacent but just above the plane surface of said slab, sliding said chase from said datum plane onto said plane surface, blowing refrigerated air over the exposed surfaces of both the chase and the slab until the temperature of the former is reduced sufficiently to allow manipulation thereof with the bare hands, pivoting said slab about the pivotal mounting therefor until that margin of the plane surface which is immediately adjacent the horizontal datum plane is raised slightly above the datum plane, the total movement of the margin of the plane surface being less than one-half inch and the angle traced 15

5

12

by the pivotal movement of the slab being bisected by said datum plane, and sliding the cooled chase off of said plane surface and onto said datum plane for further processing and use.
